UNITED STATES PATENT OFFICE.

FREDERICK J. CROLIUS, OF PITTSBURG, PENNSYLVANIA.

MECHANICAL STOKER.

No. 848,728.

Specification of Letters Patent.

Patented April 2, 1907.

Application filed May 21, 1903. Serial No. 158,080.

To all whom it may concern:

Be it known that I, FREDERICK J. CROLIUS, of Pittsburgh, Allegheny county, Pennsylvania, have invented a new and useful 5 Mechanical Stoker, of which the following is a full, clear, and exact description, reference being had to the accompanying drawings, forming part of this specification, in which—

Figure 1 is a perspective sectional view 10 showing a furnace provided with my invention. Fig. 2 is a longitudinal section thereof. Figs. 3 and 4 show in detail the grate-sections *b b*. Figs. 5 and 6 show the sections *c c*, and Figs. 7 and 8 show the sections *d d*.

15 My invention relates to an improvement in mechanical stokers for feeding the fires of boiler-furnaces and the like; and its purpose is to provide means whereby the fire will be fed and regulated more efficiently than here- 20 tofore and whereby the mechanism will be rendered more durable and easy to maintain and repair.

As shown in the drawings, the grate-surface is inclined and is composed of a series of 25 grates *b c d e*, each composed of sections detachably mounted on transverse agitating-bars 2 2, which are pivoted by trunnions 3 in side frames 4 and are rocked by a connecting bar or link 5, pivotally attached to arms 6 30 on the bars 2. The link 5 is connected to the yoke 7 of an eccentric 8, which is driven by a suitable shaft 9 and which thus reciprocates the link and causes the bars 2 2 to oscillate on their trunnions, and thus to rock the 35 grate-sections which they carry. The side frames 4 are inclined, so as to present an inclined grate-surface. The grates *b b* at the lower portion of the grate-surface are provided at their lower portions with vertical 40 slots 10, by which they are set detachably on the bars 2, and they have lateral projections at the margins of the slots, which serve to space the bars laterally from each other, and thus to afford intermediate spaces for the admission of air to the fire. These spaces do 45 not permit the dropping of the coal, because when the coal reaches the lower portion of the grate it has been coked together sufficiently to prevent its dropping through the 50 crevices. The upper grates *c c*, where the coal is yet uncoked, are likewise composed of sections having vertical slots on their under side, by which they are set on the bars 2; but instead of affording the air-spaces by separating the sections laterally they are provided 55 with horizontal or inclined wings 11 11, which

prevent the discharge of the coal, but afford free admission to the air. The grates *d d* at the top of the grate on which the coal is first delivered are preferably neither slotted nor provided with wings 11, but fit closely side by side, so as to afford an unbroken surface for the coal. They are provided at their upper margins with a flange 12, which serves to receive and deliver the coal from the dead- 60 plate as the grate is rocked.

At the base of the grate is a shaking and dumping mechanism composed of sections *e*, set on the rocking bar 2', as above described, but extending outwardly on both sides of the 70 bar to a greater distance than the other sections. The rocking bar 2', on which these sections *e* are mounted, is not connected with the link 5, but with an independent rod 13, adapted, preferably, to be operated by hand. 75 When the sections *e* are tipped by moving this rod sufficiently far in either direction, the fire may be dumped, or by shaking it to a more limited extent in both directions the clinkers can be removed from the grate without dumping the fire, and this facility for operation of the grates affords material advantages.

In the operation of my device coal is fed from a hopper to the upper portion of the 85 grate, and the eccentric 8 is started into action by means of a motor. It reciprocates the rod 5 and rocks the grates, and as they are rocked they feed the coal forward gradually and keep it in a state of agitation, thus 90 producing the best possible conditions for thorough combustion.

If any section of the grates should be damaged or burned, it may be removed and replaced readily without interfering with the 95 other sections, so that the repairing of any section involves only the replacing of the section itself and not the replacing of the entire grate.

Within the scope of my invention as defined in the claims I may make many changes in the form and construction of the parts, since

What I claim is—

1. An inclined grate having a series of 105 transverse, rocking grate-bars, the upper grate-bar being substantially imperforate, the intermediate grate-bars being provided with substantially horizontal air-spaces, and the lower grate-bars being provided with vertical air-spaces; substantially as described.
2. An inclined grate having a series of 110

transverse rocking bars, the upper bars in said series having inclined wings arranged to prevent the dropping of the fuel, and air-spaces between said wings, the intermediate 5 grate-bars of said series being provided with substantially horizontal air-spaces, and the lower grate-bars of the series being provided with substantially vertical air-spaces; substantially as described.

10 3. An inclined grate having a series of transverse rocking bars, each provided with detachable sections, the uppermost sectional bar being substantially imperforate, the intermediate sectional bars having substantially horizontal air-spaces, and the lower sectional bars having vertical air-spaces; substantially as described.

15 4. An inclined grate having a series of transverse rocking bars, the uppermost bar being substantially imperforate, the intermediate bars being formed to admit air to and 20

prevent the dropping of the fuel, the lower bars having vertical air-spaces, in combination with a dumping-grate, at the bottom of the inclined grate-surface; substantially as 25 described.

5. A grate comprising an inclined series of transverse rocking bars, having detachable sections held on said bars by gravity only, the uppermost sections forming a substantially imperforate surface, the intermediate sections having inclined wings arranged to prevent the dropping of the fuel and air-spaces between said wings, and the lower sections having vertical air-spaces; substantially as described. 30

35 In testimony whereof I have hereunto set my hand.

F. J. CROLIUS.
